CLAIM

The ornamental design for a scratching device, as shown and described.

DESCRIPTION

FIG. 1 is a front elevation view of a scratching device showing my new design;

FIG. 2 is a side elevation view thereof, the opposite side being a mirror image;

FIG. 3 is a rear elevation view thereof;

FIG. 4 is an enlarged fragmentary view showing the bottom end of the front surface, the opposed, top end being a mirror image thereof;

FIG. 5 is an enlarged fragmentary view showing the upper end of FIG. 2;

FIG. 6 is an enlarged bottom end view thereof;

FIG. 7 is an enlarged top end view thereof; and,

FIG. 8 is a perspective view thereof.
